(57) **CLAIM**

The ornamental design for a brush and roller cleaner, as shown and described.

DESCRIPTION

FIG. 1 is a perspective view of the brush and roller cleaner of the present invention;

FIG. 2 is a rear perspective view of the brush and roller cleaner of FIG. 1;

FIG. 3 is a bottom perspective view of the brush and roller cleaner of FIG. 1;

FIG. 4 is a top plan view of the brush and roller cleaner retainer of FIG. 1;

FIG. 5 is a front plan view of the brush and roller cleaner of FIG. 1;

FIG. 6 is a rear plan view of the brush and roller cleaner of FIG. 1;

FIG. 7 is a left plan view of the brush and roller cleaner of FIG. 1;

FIG. 8 is a right plan view of the brush and roller cleaner of FIG. 1; and,

FIG. 9 is a bottom plan view of the brush and roller cleaner of FIG. 1.

The broken line showing of a hose, hose attachment, appliance feet, interior portions, and exterior features shown in FIGS. 1-8 is included for the purpose of illustrating portions of the brush and roller cleaner and forms no part of the claimed design.
